UNITED STATES PATENT OFFICE.

JOSEPH DOMEcq, OF LOS ANGELES, CALIFORNIA.

DESIGN FOR A MARK-TAG FOR LAUNDRY.

48,466.

Specification for Design.

Patented Jan. 18, 1916.

Application filed July 31, 1915. Serial No. 43,032. Term of patent 14 years.

To all whom it may concern:

Be it known that I, JOSEPH DOMEcq, a citizen of the Republic of France, residing at Los Angeles, county of Los Angeles, State of California, have invented a new, original, and ornamental Design for a Mark-Tag for Laundry, of which the following is a specification, reference being had to the accompanying drawings, forming part hereof, and in which—

vational view of the same; Fig. 3 is a plan view of the same; and Fig. 4 is a side elevational view of the mark tag, approximately actual size.

I claim:

The ornamental design for a mark tag for laundry, as shown.

JOSEPH DOMEcq.
